THREAD CLEANER AND THREAD CLEANER
BLADE

Emil W. Young, Brooklyn, N. Y.

Application January 18, 1936, Serial No. 59,645

9 Claims. (Cl. 28—70)

The invention relates to thread cleaners and thread cleaner blades, such as are used on textile machines of various types for removing and detecting fluff, lint, slubs, knots, foreign matters, 5 enlargements or other imperfections from or on threads or other filaments.

It has for one of its main objects to provide a cleaner unit in which lint or other matter cannot accumulate and in which the blade may be 10 used over a long period of time without being worn. Another object is to provide a thread cleaner which will greatly relieve the strain on the traverse beam on which such cleaners are generally mounted, which will occupy small space, 15 and which will more effectively clean the threads.

Another object is to provide a thread cleaner assembly in which the blade unit may be removed from and inserted in the frame with great ease, even while the machine on which the assembly 20 is used, is running. A further object is to so attach the blade unit that it cannot be accidentally dislodged. A still further object is to provide means whereby a floating motion will be 25 imparted to the blade unit by the reciprocating action of the traverse beam.

Additional objects are to provide a thread cleaner and thread cleaner blades, of simple, accurate and strong construction, which can be readily attached to any machine where such devices are needed, in which the blade units may be 30 interchanged with a minimum expenditure of labor, and which can be manufactured at a comparatively low cost.

These and various other objects and advantages 35 will be readily understood from the following description and from the accompanying drawing of preferred embodiments of the invention, in which, however, various modifications may be made without departing from the scope of the 40 appended claims. In the drawing—

Fig. 1 is a side view of a thread cleaner unit embodying the invention;

Fig. 2 is a front view of Fig. 1;

Fig. 3 is a bottom view, taken on line A—A, 45 of Fig. 1;

Fig. 4 is another bottom view, taken on line B—B, of Fig. 1;

Fig. 5 is a view, similar to Fig. 4, showing the cleaner blades in a different position;

Fig. 6 is a fragmental, cross-sectional, side view of certain parts of the thread cleaner unit;

Fig. 7 is a similar view, showing the blade locking mechanism in its open position;

Fig. 8 is a side view of a thread cleaner employing a somewhat modified frame; and

Fig. 9 is a front view of Fig. 8.

Referring first to Figs. 1 to 7, the cleaner unit consists of a frame 10 which is bent rearwardly at 11 and downwardly at 12, as plainly shown in Fig. 1. Slots 13 are provided at the upper end of the frame and the frame is shown attached to the traverse beam 14 of a textile machine, by means of screws 15. A bracket 16 is sheared from the center of the frame and bent downwardly and inwardly under the part 11 of the frame and parallel with this part.

The cleaner blade unit, which consists of a blade support 17 and a pair of cleaner blades 18, is supported between the bracket 16 and the rearwardly bent part 11 in the manner to be explained later. A thread guide 19 is secured at the lower end 12 of the frame, while a socket 20 is sheared and bent outwardly from the frame to support another thread guide 21 which is supported on a wire frame 22. The lower ends of this frame fit 20 in the socket 20. This wire frame is so constructed as to make it easy to insert the thread 23 in the guide 21.

The cleaner blade unit is secured to the frame in the manner plainly illustrated in Figs. 6 and 25 7, to which reference is now made. A flat spring 24 is secured to the upper side of the part 11 of the frame and extends in underneath the brackets 16. A pin 25 is riveted to this spring. The pin is provided with an enlarged head 26 which 30 is slidingly mounted in a hole 27, formed in the part 11, while the pin itself slides in a hole 28, formed in the bracket 16. The spring 24 normally tends to hold the pin 25 in the position 35 shown in Fig. 6. The blade support 17 is provided with an elongated hole 29 in which the head 26 fits and a slot 30, slightly larger than the diameter of the pin 25, extends from the hole 29 to the rear end of the blade support.

This construction of the blade support is plainly shown in Figs. 3, 4, and 5. It will be noted 40 that the blade support, when the pin is in the position shown in Fig. 6 may swing on the head 26 and move slightly in and out in relation to the frame. It will also be noted that when the pin is forced upward against the tension of the spring 24, as illustrated in Fig. 7, that the head 45 will be raised above the blade support so that in this position the blade unit may be removed by 50 pulling the blade forward so that the slot 30 will straddle the pin 25. Thus, by raising the pin 25, the cleaner blade units may be removed or inserted in the frame. An opening 31 is also 55 formed in the spring so that the head 26 may

pass through this opening when raised to release the cleaner blade unit.

Reference is now made to Figs. 3, 4 and 5. As previously stated, the blade unit is free to swing on the head 26 and is also provided with a sliding movement, due to the elongation of the opening 29. As the traverse beam 14 moves back and forth, the jar, caused by the reversal of the beam, will cause the blade unit to swing first to one side and then to the other, as the beam reciprocates, as plainly illustrated in Figs. 4 and 5. To limit this swinging movement, stop pins 32 and 33 are provided.

By providing cam faces in the side of the blade support, such as are shown at 34 and 35, it is possible to impart a positive sliding movement to the blade unit each time that the traverse beam reverts its stroke. In Fig. 3, the blade is shown at right angles to the frame and with the blade unit pushed into the frame as far as it will go. As the blade is swung by the reversal of the traverse beam, as shown in Fig. 4, the pin 33 enters into the cam notch 35 and holds the blade unit in this position in relation to the frame. However, when the traverse beam is reversed so that the blade support strikes the pin 32, as in Fig. 5, the cam notch 34 causes the blade unit to be pulled forward to the position shown. Thus on each reciprocation of the traverse beam the blade unit is not only pivoted from one side to another, but moved in and out, as plainly shown in Figs. 4 and 5. This is a very important feature and its advantages will be explained later.

In Figs. 8 and 9 a somewhat modified frame 35 is shown. This frame 35A, is provided with a bracket 36, similar to the one previously described, and also with a similar spring 37 which operates the pin 38 to hold the blade support 39 on which the cleaner blades 40 are secured. On the upper end of the frame, two tubular members 41 and 42 are formed, in each of which one leg 43 of a U-shaped member is rigidly secured. The other legs 44 of these U-shaped members are adapted to be inserted in openings 45 drilled in the device on which the thread cleaner is to be used. In this instance the device 46 is an ordinary tension device through which the thread 47 passes. The thread is supported in a thread guide 48 secured on the lower side of the frame. To reduce the friction between the cleaner blade support and the bearing formed by the part 11 and the bracket 16, these last mentioned parts are preferably cupped, as shown at 49 and 50 in Fig. 6, or a small circular bead 51 is raised, as shown in Fig. 7. This makes the blade support respond more readily to the movement of the traverse beam. The blades 18 may be secured to the blade support in any suitable manner. A slot 52, of considerably greater width than the thread cleaning opening 53 between the blades, is provided in the blade support.

It will be noted that the swinging movement of the blade unit is caused solely by the jarring or vibration of the traverse beam, or other movable parts on which the frame may be attached. The movement of the thread itself does not impart any swinging movement to the blade unit as the thread is guided on both sides of the blade unit, as for example by the guides 19 and 21. However, under certain circumstances, the thread will impart a sliding movement to the blade unit, as for example when a heavy slab is encountered. In such cases the blade unit is pulled either in or out, as the case may be. This imparts a shear-

ing action to the blade which greatly facilitates the removal of such slabs or other enlargements.

It has been found in practice that the sliding movement of the blade enables so-called "raw" knots to pass freely between the blades. It will also be evident that the sudden jarring imparted to the blade unit, at each end of the strokes of the traverse beam, will shake off and dislodge any lint or other foreign matter which may tend to accumulate on the cleaner blades. By extending slots 53 some distance back of the rear end of the cleaner blades this removal of lint and other matter is greatly facilitated. Due to the sliding movement of the blades, the wearing action of the thread on the cleaning surfaces of the blades is greatly reduced in that the thread does not continuously pass over the same parts of the blades.

It is evident that, by shaping the brackets as shown in Fig. 1, the main weight of the whole device is directly underneath the beam and not in front of the beam as is generally the case. This prevents tilting of the traverse beam and greatly prolongs its life. It will also be seen that the removal of the blade unit or substitution of other blade units, is easily accomplished by merely compressing the spring 24. Inasmuch as this spring is quite some distance back of the thread, this may even be accomplished without stopping the travel of the thread.

Having described my invention and its objects, what I claim as new and wish to protect by Letters Patent is:

1. A thread cleaning device comprising a frame having a bifurcated bracket for receiving a cleaner blade unit; means for securing the frame to a reciprocating part of the machine on which employed; a pin mounted transversely in said bracket; a cleaner blade unit having an elongated slot; the pin of the bracket engaged in said slot; and means associated with the frame and with the blade unit for causing the blade unit to slide in and out on said pin as the reciprocating part, on which the device is mounted, is actuated.

2. A thread cleaning device comprising a frame having a bifurcated bracket for receiving a cleaner blade unit; means for securing the frame to a reciprocating part of the machine on which employed; a pin mounted transversely in said bracket; a cleaner blade unit having an elongated slot; the pin of the bracket engaged in said slot; and means associated with the frame and with the blade unit for causing the blade unit to slide in and out on said pin as the reciprocating part, on which the device is mounted, is actuated; said means comprising angular notches cut on opposite sides of the blade unit and pins mounted on the frame for engagement with said notches as the blade unit swings from side to side.

3. A thread cleaning device comprising a frame having a bifurcated bracket for receiving a cleaner blade unit; means for securing the frame to a reciprocating part of the machine on which employed; a pin, having an enlarged head mounted transversely in said bracket; a cleaner blade unit having a slotted end terminating in an elongated opening of a width equal to the diameter of the head on the pin; the head of the pin engaged in said slot; and means associated with the frame and with the blade unit for causing the blade unit to slide in and out in the socket as the reciprocating part, on which the device is mounted, is actuated.

4. A thread cleaning frame having means for securing it to a reciprocating part of the ma-

chine on which employed; a bifurcated bracket, for receiving a cleaner blade unit, provided on said frame; a pin, having an enlarged head, slid-
5 ingly mounted transversely in said bracket; means for lifting said pin while a blade unit is being inserted or removed; spring means for re-
turning the pin to its normal position; and a pair
10 of pins so located on the frame as to straddle the blade unit when inserted in the bracket and engaged with angular notches cut on opposite sides of the blade unit.

5. A blade unit, adapted to be inserted in the bracket of a thread cleaner frame having a trans-
verse pin with an enlarged head secured in the
15 bracket and spaced pins adapted to straddle the blade unit; a slot formed in one end of said unit and terminating in an enlarged opening adapted to fit slidingly over the head of the pin in the bracket; and angular notches cut in the side of
20 the blade unit for engagement with the pins secured on the frame on which the blade unit is employed.

6. A thread cleaning device comprising a frame having means for swingably supporting a thread
25 cleaner unit; means for securing the frame to a reciprocating part of the machine on which em-
ployed; and means associated with the frame and with the blade unit for causing the blade unit to reciprocate in relation to the frame as
30 the reciprocating part, on which the device is mounted, is actuated.

7. A thread cleaning device comprising a frame having means for swingably supporting a thread cleaner unit; means for securing the frame to a reciprocating part of the machine on which em-
ployed; and means associated with the frame and with the blade unit for causing the blade unit to reciprocate in relation to the frame as the re-
ciprocating part, on which the device is mounted, is actuated; said means comprising angular notches cut on opposite sides of the blade unit 10 and pins mounted on the frame for engagement with said notches as the blade unit swings from side to side.

8. A thread cleaner frame having means for securing it to a reciprocating part of the machine 15 on which employed; a socket for swingably sup-
porting a cleaner blade unit having notches formed on its opposite edges; and pins secured on the frame for engagement with said notches to cause the blade unit to reciprocate when the 20 part on which the device is secured is actuated.

9. A blade unit having means for swingably se-
curing it to a thread cleaner frame on which a pair of spaced pins are rigidly secured, notches 25 formed on the opposite edges of the blade unit, and said notches adapted to be engaged by the pins on the cleaner frame as the blade unit swings from side to side.
